(57) **CLAIM**

The ornamental design for a golf club head, as shown and described.

DESCRIPTION

FIG. 1 is a perspective view of a golf club head, the broken line showing of a shaft is for illustrative purposes and forms no part of the claimed design;

FIG. 2 is an enlarged perspective view of the head;

FIG. 3 is a perspective view from the rear;

FIG. 4 is a top plan view;

FIG. 5 is a front elevation;

FIG. 6 is a right side elevation;

FIG. 7 is a left side elevation;

FIG. 8 is a rear elevation;

FIG. 9 is a bottom plan view;

FIG. 10 is a front perspective of a second embodiment of the golf club head as disclosed in FIG. 1; and,

FIG. 11 is a left side elevation of the modified form of the design.

The undisclosed sides of the second embodiment are identical to those disclosed in the first embodiment.
